UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

WELDING.

1,374,640.

Specification of Letters Patent. Patented Apr. 12, 1921.

Application filed July 21, 1920. Serial No. 397,915.

To all whom it may concern:

Be it known that I, ETHAN I. DODDS, a citizen of the United States, and a resident of Pittsburgh, in the county of Allegheny and State of Pennsylvania, have invented 5 certain new and useful Improvements in Welding; and I do hereby declare the following to be a full, clear, and exact description of the invention, such as will enable 10 others skilled in the art to which it appertains to make and use the same.

This invention relates to improvements in welding and particularly to the welding of closures to boiler sheets adjacent to the connection of the staybolts with the latter,— 15 one object of the invention being to provide a simple portable and efficient manner of butt-welding a cap or closure to the boiler sheet whereby the abutting portions of the 20 cap or closure and the boiler sheet shall be so fused as to become integral the one with the other and thus to eliminate danger to the person of the operator, which might be incident to a greater or less extent, to the 25 employment of what is known as a "plastic" weld.

A further object is to so butt-weld a cap or closure to the boiler sheet that a homogeneous, steam-tight union shall be insured.

With these and other objects in view, the 30 invention consists in certain novel features as hereinafter set forth and pointed out in the claims.

In the accompanying drawings; Figure 1 35 is a plan view of a device for use in applying a cap or closure to a boiler sheet; Fig. 2 is a sectional view, partly in elevation; Fig. 3 is a diagrammatical view, and Figs. 4, 5 and 6 are views showing modifications.

1 represents an outer boiler sheet having 40 a bolt opening 2, the latter being formed to provide a seat 3 for the head 4 of a staybolt 5.

The head of the staybolt is covered and 45 the opening in the boiler sheet is seated by means of a cap or closure 6 (which is butt-welded to the boiler sheet as hereinafter described) and said cap or closure is made

in such size and proportions as to provide a clearance space 7 for head of the staybolt. 50

8 represents an electro-magnet having a general U-shape so that its poles may be placed against the boiler sheet distances from the position which the closure 6 is to occupy, and the coils 9 of said magnet are 55 included in an electric circuit 10, the latter including a suitable source of direct current (such as a battery 11) and a switch 12.

The intermediate portion 13 of the core of the magnet 8 constitutes a fulcrum for 60 the hook-shaped end 14 of the short arm of a lever 15. The long arm of the lever constitutes a handle of considerable length and at the juncture of the long and short arm of the lever, the latter is enlarged and 65 may be made with a recess or socket 16 having an insulating lining 17. The enlarged portion of the lever may also be made with an opening having a tubular insulating lining 18. A plunger 19, which constitutes an 70 electrode to engage the cap or closure, may be movably mounted in the recess of the lever and is provided with a rod or stem 20 which passes through the tubular lining and beyond the top of the lever. Disks 21 may 75 be provided on the rod or stem 20 to receive an electric conductor between them and a nut 22 may be threaded on said rod or stem to clamp said conductor between the disks. The rod or stem 20 thus constitutes a binding post on the electrode or plunger. The 80 lower end of the electrode or plunger 19 may be made concave to conform approximately to the contour of the cap or closure and a strong spring 23 located within the 85 recess of the lever may exert a downward pressure on the plunger and the cap or closure.

The secondary winding of a transformer 24 is connected in a circuit 25 with the 90 boiler plate 1 and the plunger 19,—one terminal (26) of said circuit being connected with the stem or binding post 20 and the other terminal (27) being connected with the boiler sheet. A suitable switch 28 will 95 be included in the circuit 25. The primary

of the transformer 24 is connected in a circuit 29 with an alternating current generator 30 and a switch 31,—an adjustable inductive resistance 32 being also included in 5 said circuit 25.

The cap or closure 6 is placed on the boiler sheet around the bolt opening and over the head of the staybolt, with a small quantity of spelter interposed between the flat edge 10 of the cap or closure and the face of the boiler sheet, and said cap or closure will be held properly in position by the plunger 19,—the lever carrying said plunger having been connected with the magnet and the latter 15 having been properly positioned on the boiler sheet and the circuit of its coils closed. The generator 30 having been started, the circuit 25 including the secondary of the transformer, may now be closed and pressure 20 applied to the lever 15. The pressure of the spring 23 and that applied to the lever, will be transmitted through the plunger 19 to the cap or closure 6, and while the cap or closure is thus under pressure, and the 25 greatest resistance in the circuit 25 occurring between the edge of the cap or closure and the adjacent portion of the boiler sheet, these parts of the metal of the cap and boiler sheet will become fused and welded together, 30 making the cap or closure and boiler sheet integral, the one with the other, and effecting a homogeneous steam-tight union.

Instead of making the part which carries the plunger in the form of a lever having 35 pivotal connection with the magnet as shown in Figs. 1 and 2,—the core or frame of the magnet may be provided with an integral arm 33 having a head 34 as shown in Fig. 4, said head carrying the spring-pressed 40 plunger 19, and in this instance, the spring and the holding force of the magnet against the boiler sheet may both be utilized to supply the necessary pressure on the cap or closure during the welding operation. If desired, the device may be provided with a handle 35 as shown in Fig. 4.

In the form of the invention shown in Fig. 5, the spring is dispensed with and an electrode 36 secured in the lever 15 and insulated therefrom as indicated at 37.

In the construction shown in Fig. 6, the electro-magnetic frame or structure comprises a plurality of arms 38 radiating from a central portion 39 and each arm is provided with a coil 40. The coils 40 are connected in series in circuit with a battery 11 and a suitable switch 12. The central portion 39 of the magnetic frame or structure is made with an opening which receives the 55 electrode, the binding post of which is shown at 41,—it being understood that said plunger and its binding post are suitably insulated from the magnet frame or structure.

Having fully described my invention what I claim as new and desire to secure by 65 Letters Patent, is:—

1. Welding means comprising a pressure-applying member, an electromagnetic structure constituting connecting means for said member, and means for including parts to 70 be welded in an electric circuit to effect a welded union of said parts while under pressure of said pressure applying means.

2. A welding means comprising a magnetic structure, a member projecting therefrom, a spring-pressed plunger carried by 75 said member and adapted to engage a part to be welded to another part, and means for including said plunger and the parts to be welded together in an electric circuit 80 to effect a welded union of said parts.

3. Welding means comprising an arm provided with an insulated part to engage a part to be welded, an electromagnetic structure from which said arm projects, 85 and an electric welding circuit including said insulated part.

4. Welding means comprising an arm, a spring-pressed plunger carried by said arm, an electromagnetic structure from which 90 said arm projects, and an electric welding circuit including said plunger.

5. Welding means comprising an electromagnetic structure, a lever fulcrumed to 95 said magnetic structure, an insulated part to engage a part to be welded, said insulated part located near the fulcrumed end thereof, and an electric welding circuit including said insulated part.

6. Welding means comprising an electromagnetic structure, means for controlling the same, an arm projecting from said electromagnetic structure, an insulated member carried by said arm for engaging a part to be welded, an alternating current generator, a transformer having one of its coils included in circuit with said generator, a welding circuit including the other coil of the transformer and said insulated member, and regulating means for said welding 110 circuit.

7. Welding means comprising an electromagnetic structure, and an insulated member carried by said electromagnetic structure and constituting an electrode to engage 115 a part to be welded to another part, and an electric welding circuit including said electrode.

8. In welding means, the combination with an electromagnetic structure for application to a boiler sheet, of an electrode to engage a cap or closure, connected with and insulated from said electromagnetic structure, and an electric welding circuit including said electrode.

9. In a welding means, the combination

with an electromagnetic structure for application to a boiler sheet, of a lever connected with said electromagnetic structure, an electrode to engage a cap or closure, carried by and insulated from said lever, and an electric welding circuit including said electrode.

10. The herein described method of welding a cap or closure to a boiler sheet, consisting in placing a cap or closure over an opening in the boiler sheet, connecting pres-

sure means magnetically to the boiler sheet, exerting pressure with said means on the cap or closure and simultaneously including said cap or closure and boiler sheet in 15 an electrical welding circuit.

In testimony whereof, I have signed this specification in the presence of a subscribing witness.

ETHAN I. DODDS.

Witness:

EDWIN S. RYCE.
